DESIGN FOR A SLIPPER

Israel Berman, Little Falls, N. Y.

Application September 2, 1936, Serial No. 64,685

Term of patent 3½ years

To all whom it may concern:

Be it known that I, Israel Berman, a citizen of the United States of America, residing in Little Falls, county of Herkimer and State of New York, have invented a new, original, and ornamental Design for a Slipper, of which the following is a specification, reference being had to the accompanying drawing, forming part thereof,

Fig. 1 is a plan view of a slipper showing my new design.

Fig. 2 is a side elevational view of a slipper as shown in Fig. 1.

The essential feature of my design resides in the placement of a bow-like element of ornamentation of a contrasting color within the lamb's wool cuff surrounding the upper edge of a slipper, as shown, the four ends of the bow being permanently attached to the cuff, thus presenting the same constant appearance at all times.

I claim:

The ornamental design for a slipper substantially as shown and described.

ISRAEL BERMAN.
